Translation of the Taiwanese Search Report for Taiwanese Design Patent Application No. 108305982, completed Jun. 2, 2020, 1 page.

Primary Examiner — Ramzi S Almatrahi(74) *Attorney, Agent, or Firm* — Tucker Ellis LLP(57) **CLAIM**

The ornamental design for a camera, as shown and described.

DESCRIPTION

FIG. 1 is a top, front and left side perspective view of a camera showing our new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines illustrate portions of the camera that form no part of the claimed design.
